(57) CLAIM

The ornamental design for a table, as shown and described.

DESCRIPTION

FIG. 1 is a top, front, left perspective photographic view of a table showing our new design;

FIG. 2 is a top photographic view thereof;

FIG. 3 is a front photographic view thereof;

FIG. 4 is a rear photographic view thereof;

FIG. 5 is a right side photographic view thereof; and,

FIG. 6 is a left side photographic view thereof.

The broken lines depicting the remainder of the table form no part of the claimed design.

1 Claim, 6 Drawing Sheets
